[57] CLAIM

The ornamental design for a diaper bag pocket, as shown.

DESCRIPTION

FIG. 1 is a front perspective view of a diaper bag pocket embodying our design, and showing the pocket closed;

FIG. 2 is a front perspective view of the diaper bag pocket of FIG. 1 and showing the pocket open;

FIG. 3 is a front elevational view of the open diaper bag pocket;

FIG. 4 is a right side elevational view of the open diaper bag pocket, with the left side being a mirror image thereof;

FIG. 5 is a rear elevational view thereof;

FIG. 6 is a top plan view thereof; and,

FIG. 7 is a bottom plan view thereof.

The broken line showing of a purse in FIGS. 1 and 2 is for illustrative purposes only and forms no part of the claimed design.
